UNITED STATES PATENT OFFICE.

JAMES M. THOMPSON, OF MILWAUKEE, WISCONSIN, ASSIGNOR TO LUTHER BROS. CO.,
OF MILWAUKEE, WISCONSIN, A CORPORATION OF WISCONSIN.

TOOL-DRIVING MECHANISM.

1,104,747.

Specification of Letters Patent.

Patented July 21, 1914.

Application filed March 31, 1910. Serial No. 552,573.

To all whom it may concern:

Be it known that I, JAMES M. THOMPSON, a citizen of the United States, residing at Milwaukee, county of Milwaukee, and State 5 of Wisconsin, have invented new and useful Improvements in Tool-Driving Mechanism, of which the following is a specification.

My invention relates to improvements in foot power driving mechanism for grinding 10 wheels, boring tools, etc.

The object of my invention is to provide a form of construction in which the various tools may be adjusted in any desired position with reference to the operator, in accordance with the character of the work to 15 be performed.

A further object of my invention is to provide a form of construction which can be readily adjusted to suit the convenience of 20 the operator, it being recognized that different operators require different adjustments.

In the following description, reference is had to the accompanying drawings, in which—

25 Figure 1 is a side elevation of my invention, showing the upper gear casing in section, and also showing a grinding wheel mounted upon the driven shaft. Fig. 2 is a front elevation of the same, the upper 30 casing being also shown in section. Fig. 3 is a detail side view of a modified seat support.

Like parts are identified by the same reference characters in both views.

35 A standard 1, the upper portion of which is tubular, is provided with a supporting brace 2, having a cross piece 3 at its lower end, whereby the standard is supported in a vertical position. The brace 2 is secured to 40 the upper portion of the standard by clamping plates 5 connected with each other in clamping position by bolts 6 and thumb nuts 7. Said plates comprise a pair of members formed with semi-cylindrical 45 standard engaging portions to engage the standard and flat surfaced portions between which portions of the respective plates, the brace 2 is engaged. A seat supporting bar 8 is similarly secured to the standard by 50 means of clamping plates 9, a single clamping bolt 10 being employed to connect this plate with the bar 8. The plates 9 are similar to the plates 5 in form and arrangement. The bar 8 is also secured to the 55 brace bar 2 by a member 12, which is mov-

able longitudinally of the bar 2, and may, if desired, be clamped thereto in any position of adjustment, by means of suitable set screws or bolts. The bar 8 extends beyond the brace bar 2 and is provided with a seat 13 of any ordinary type. A gear casing 15 is mounted upon the standard 1, from which it is supported by clamping plates 16, bolts 17 and nuts 18. These nuts are preferably thumb nuts, so that they can be readily adjusted to clamping or releasing position. The upper end of the standard 1 has a cylindrical outer surface, so that when the nuts 18 are loosened, the casing 15 may be rotated upon the standard.

60 A shaft 21 is journaled in suitable bearings at 22 and 23 in the casing 15, and motion is transmitted to this shaft from pedal cranks 25, through the crank shaft 26, bevelled gear wheel 27, pinion 28, vertical shaft 29, bevelled gear wheel 30, and pinion 31, the latter being fast on shaft 21. In the drawings, I have illustrated the shaft 21 as provided at one end with a grinding wheel 33 and at the other end with a drill 34. Both 65 the grinding wheel and the drill are detachably connected with the shaft 21, so that they can be readily removed and other tools substituted therefor. In Fig. 1, I have illustrated a single rest 35 of ordinary type, removable connected with the casing 15 at 37. Tool rests of various descriptions, or other work holders, may be substituted for the 70 single rest 35 in an obvious manner.

75 With the above described construction, it will be apparent that the seat supporting bar 8 may be raised or lowered to any desired height in accordance with the requirements of the user since it may be clamped to the brace and standard at any desired 80 height. It may also be tilted at any desired angle by adjusting the clamping plates 9 vertically on the standard 1 without making a relative change in the position of the supporting members 12 on the brace bar 2. 85 It will also be observed that the tubular portion of the standard 1 terminates immediately above the pinion 28, the standard having an offset portion 39, affording clearance for the pinion and a base portion 41 90 provided with a bearing 42 for the shaft 26. It will also be observed that the holding member 12 may be connected with the brace bar 2 by a central bolt 43, the bar 8 being slotted at 44 to permit the same to move 95 100 105 110

longitudinally, when the bolt 43 is loosened and the bar 2 being also slotted longitudinally, as shown at 45 to permit raising and lowering the member 12. But the specific construction of the standard and the specific construction of the clamping members and the supporting member 12, as shown and described, are not essential to my invention. In Fig. 3 I have illustrated a pair of bars 8, 10 which are clamped upon the brace 2 by clamping members 47 and bolts 48. The seat is not illustrated in this view but it will be understood that a seat similar to that illustrated in Fig. 1 may be employed, which 15 is adjustable along the bar or bars 8 to suit the requirements of the operator.

Having thus-described my invention, what I claim as new, and desire to secure by Letters Patent, is—

20 1. A foot power driving mechanism comprising a standard having a base portion adapted to rest upon the floor and provided with an upright tubular upper portion, a support having adjustable swivel connection with 25 the upper portion of the standard, means for locking the same to the standard in any desired position of rotative adjustment, a crank shaft journaled in said base and provided with foot pedals, a vertical shaft 30 journaled in the tubular standard and provided with gear wheels at its upper and lower ends, a gear wheel on the crank shaft in mesh with the gear wheel on the vertical shaft, and a driven shaft provided with a

gear wheel in mesh with the upper gear wheel on the vertical shaft and journaled in said support, said driven shaft being adapted for direct connection of suitable tools therewith, and said tools being adapted to operate at any angle in a horizontal 40 plane about said standard, by appropriate adjustment of said support.

2. A foot power driving mechanism comprising a standard having a base portion adapted to rest upon the floor and provided 45 with an upright tubular upper portion, a support having adjustable swivel connection with the upper portion of the standard, means for locking the same to the standard in any desired position of rotative adjustment, 50 pedal and crank mechanism journaled in said base, a vertical shaft journaled in the tubular standard and driven from the pedal and crank mechanism, and a driven shaft operatively connected with the vertical shaft 55 and journaled in said support, said driven shaft being adapted for direct connection of suitable tools therewith, together with a brace bar extending angularly from the upper portion of the standard to the floor, a 60 seat bar adjustably connected with the brace bar, and a seat mounted on said seat bar.

In testimony whereof I affix my signature in the presence of two witnesses.

JAMES M. THOMPSON.
